UNITED STATES PATENT OFFICE.

ROBERT SNEIDER, OF BROOKLYN, NEW YORK.

DESIGN FOR A CHRISTMAS-CARD.

SPECIFICATION forming part of Design No. 14,992, dated May 6, 1884.

Application filed January 11, 1884. Term of patent 14 years.

To all whom it may concern:

Be it known that I, ROBERT SNEIDER, a resident of Brooklyn, Kings county, State of New York, have invented a new and original Design for Christmas-Cards, of which the following specification is a full, clear, and exact description, reference being had to the accompanying drawing, forming part of this specification.

10 The drawing represents a face view of my newly-designed Christmas-card.

This design is for a Christmas-card or other similar article.

It consists of a card, A, having an outer

border, a, and an inner border, b, both of the 15 description hereinafter pointed out. The outer border, a, represents an ornamental strip displayed on the face of card A at its edge. The inner border, b, represents fringe or lace.

The card A has a central design, c.

I claim as my invention—

The design for card A, having outer border, a, and inner border, b, representing fringe or lace, as described and shown.

ROBERT SNEIDER.
